Primary Examiner — Vy N Koenig(74) *Attorney, Agent, or Firm* — Michael Best & Friedrich LLP(57) **CLAIM**

We claim the ornamental design for a stool, as shown and described.

DESCRIPTION

FIG. 1 is a perspective view of a stool embodying the invention.

FIG. 2 is a rear view of the stool of FIG. 1.

FIG. 3 is a front view of the stool of FIG. 1.

FIG. 4 is a first side view of the stool of FIG. 1.

FIG. 5 is a second side view of the stool of FIG. 1.

FIG. 6 is a top view of the stool of FIG. 1.

FIG. 7 is a perspective view of another stool embodying the invention.

FIG. 8 is a rear view of the stool of FIG. 7.

FIG. 9 is a front view of the stool of FIG. 7.

FIG. 10 is a first side view of the stool of FIG. 7.

FIG. 11 is a second side view of the stool of FIG. 7; and,

FIG. 12 is a top view of the stool of FIG. 7.

The broken lines in the drawings depict portions of the stool that form no part of the claimed design.
